UNITED STATES PATENT OFFICE.

FRANK VICTOR POLAKOSKEY, OF PEEKSKILL, NEW YORK.

CLOTHES-LINE PULLEY.

No. 852,740.

Specification of Letters Patent.

Patented May 7, 1907.

Application filed August 18, 1906. Serial No. 331,136.

To all whom it may concern:

Be it known that I, FRANK VICTOR POLAKOSKEY, a citizen of the United States, and a resident of Peekskill, in the county of Westchester and State of New York, have invented 5 certain new and useful Clothes-Line Pulleys, of which the following is a specification.

This invention relates to endless clothes-lines pulleys, and has for its particular object 10 a pulley adapted to the use of a clothes pin that forms the subject of my application for a patent, No. 307,162, filed March 21, 1906, whereby the pin will follow the clothes-line around the pulley without any chance for 15 dislodgment, or of forming, or meeting with any obstruction.

The object is attained by the means set forth in these specifications and the accompanying drawings, in which like letters refer to 20 similar parts throughout the several views.

Figure I is a side view of the pulley. Fig. II is a top view of the pulley. Fig. III is a front view of the pulley showing the clothes-line in cross-section and a clothes pin on the 25 line.

A view of the clothes pin referred to is shown at *m*, Fig. III. It is provided with extended spring-arms *n' n*, the latter shaped to the line, and adapted to open when the pin 30 is opened. Instead of the pin being used to pin the clothes on the line, one end of the pin grasps the garment and the other end of the pin clamps over the line, the pin hanging on the line, the garment from the pin.

The upper half of Fig. I, above the line 1, represents an ordinary sheave, the yoke *A* having the hook-eye *d* and the broadened part *e* to be riveted to the sheave *a*, a pivot *i* extending through the sheave and the wheel 40 *b*. The lower half, however, is quite different. The lower half of the sheave *a* is the same as the upper half, and the lower half *f* of the yoke *A* is the same up to where it would change its form to be united with the sheave, 45 at which point it is provided with extensions that are curved concentric with the sheave, but having a larger radius than the sheave, and dropping below the sheave, as in Figs. II and III. These curved arms have no con-

nexion with the under side of the sneave. 50 The difference between the radii of the sheave and the arms is such as to give a vertical clearance between the two, as at *l*, Figs. I and II, to allow for the passage of the clothes pins.

In the end view of the pulley in Fig. III, *o* represents the clothes line, and *n' n* the clothes pin. The pin will hang vertically from the line, and the curved parts *n* will readily adapt themselves to the groove 60 in the pulley. The straight parts *n'* of the pin will lie together parallel or nearly so, and as the pin approaches the pulley the rounded points *2, 2* of the arms will guide the pins into the channel *z*. It will be obvious that the 65 pin cannot be displaced from the line, nor is there any way for its passage around the pulley to become obstructed.

The sheave *a* and the yoke *A* may be made in one piece as well as in two as shown. 70

Having described my invention, what I claim and desire to secure by Letters Patent, is—

1. The combination of a sheave and pulley with a yoke, attached thereto, one arm of the 75 yoke secured to one side of the sheave with the open end of the sheave toward the closed end of the yoke, the other arm of the yoke bifurcated and extended around the free side of the sheave away from the plane of the pulley. 80

2. The combination of a sheave and pulley with a yoke, the yoke attached to one side of the sheave with the open end of the sheave toward the closed end of the yoke, an eye on 85 the yoke, the free arm of the yoke divided and curved around the free side of the sheave with a radius greater than that of the pulley and sheave and in a plane away from that of the pulley. 90

Signed at Peekskill in the county of Westchester and State of New York this thirteenth day of August A. D. 1906.
